UNITED STATES PATENT OFFICE.

LANSING ONDERDONK, OF NEW YORK, N. Y.

DESIGN FOR A SEWING-MACHINE FRAME.

SPECIFICATION forming part of Design No. 34,670, dated June 18, 1901.

Application filed May 21, 1901. Serial No. 61,314. Term of patent 14 years.

To all whom it may concern:

Be it known that I, LANSING ONDERDONK, a citizen of the United States, residing at New York, in the county of New York, State of New York, have invented a certain new and original Design for Sewing-Machine Frames, of which the following is a description, reference being had to the accompanying drawing, and to the letters of reference marked thereon.

My invention relates to a new and original design for a sewing-machine frame; and it consists of a sewing-machine frame of the shape and configuration hereinafter described, and illustrated in the accompanying drawing, in which the figure represents a perspective view of a sewing-machine frame embodying my design.

In the drawing, A represents the gooseneck or overhanging arm of the frame, and which

rises from the base B. The base B has a flattened part C and then an angular extending transversely-curved part D, from which rises the cylindrical post portion E, and from this projects to a point beneath the gooseneck A ²⁵ the cylindrical portion F of the machine-frame.

The leading feature of the design consists of the frame, substantially as illustrated.

Having thus described my invention, what I claim is—

The design for a sewing-machine frame; substantially as shown and described.

In testimony whereof I affix my signature in presence of two witnesses.

LANSING ONDERDONK.
